UNITED STATES PATENT OFFICE

HERBERT L. BONE, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY BRAKING APPARATUS

Application filed September 24, 1928. Serial No. 307,895.

My invention relates to railway braking apparatus, and particularly to apparatus of the type comprising braking bars located in the trackway and arranged to be moved at 5 times into engagement with the wheels of a railway car.

I will describe one form of apparatus embodying my invention, and will then point out the novel features thereof in claims.

In the accompanying drawings, Fig. 1 is a top plan view showing one form of braking apparatus embodying my invention with some of the parts broken away to illustrate the construction. Fig. 2 is a view partly in 10 elevation and partly in section along the line II—II of Fig. 1. Fig. 3 is a sectional view along the line III—III of Fig. 1. Fig. 4 is a sectional view showing a portion of the apparatus illustrated in Fig. 1 on a somewhat 15 larger scale. Figs. 5 and 6 are views showing, in elevation and top plan, respectively, one of the trunnions D and the associated resilient link G forming part of the apparatus illustrated in Fig. 1. Fig. 7 is a sectional 20 view illustrating the equalizing device E forming a part of the apparatus illustrated in Fig. 1. Fig. 8 is a detailed view showing the connection between a driving bar and a braking bar in the apparatus shown in Fig. 25 1. Fig. 9 is a detailed view showing the arrangement of the parts by means of which motion is transmitted to a driving bar in the apparatus of Fig. 1. Fig. 10 is a top view of the driving link 38 shown in Fig. 9. Fig. 11 30 is a diagrammatic view showing one form of apparatus for controlling the motor M of Fig. 1, and also embodying my invention. Fig. 12 is a detail view showing a portion of the apparatus illustrated in Fig. 4 and also 35 embodying my invention.

Similar reference characters refer to similar parts in each of the several views.

Referring first to Figs. 1, 2 and 3, the reference characters 1 and 1^a designate the track 40 rails of a stretch of railway track supported by cross ties 2 in the usual manner. Extending parallel with rail 1 are two pairs of stringers, one pair 8 and 9 being located on one side of the track rail, and the other pair 45 10 and 11 being located on the other side of

the track rail as best shown in Fig. 3. The two pairs of stringers are connected together at intervals by means of yokes, each designated by the reference character 12 and extending transversely beneath the track rail 50 and having one end interposed between stringers 8 and 9 and the other end between stringers 10 and 11. The stringers are securely fastened to the yokes 12 as shown in detail in Fig. 4, and it will therefore be plain 55 that the four stringers 8, 9, 10 and 11, together with the yokes 12 form a cradle for supporting the braking apparatus. In similar manner, rail 1^a is provided with a cradle 60 made up of four stringers 8^a, 9^a, 10^a, and 11^a, and a plurality of yokes 12^a. Located in the upper surface of each of the yokes 12 are two channels 13, one located on each side of the associated rail and each provided with two over-turned ears 14. One of these channels is shown in detail in Fig. 4. These 65 channels form guides for driving bars which extend the full length of the braking apparatus. For example, driving bars 3 and 4 are located in the channels of the yokes 70 12 associated with rail 1, one of these driving bars being located on each side of the rail. In similar manner, driving bars 3^a and 4^a, one located on each side of rail 1^a, occupy the 75 channels 13 in the yokes 12^a associated with rail 1^a.

The reference character M designates a motor for operating the driving bars 3, 4, 3^a, and 4^a. As here shown, this motor comprises a cylinder 18 containing a piston 19 which 80 may be reciprocated by means which I will describe hereinafter. The piston 19 is attached to a plunger 21, the free end of which is connected, by means of a link 22 with a lever 23. The lever 23 is pivoted at 24 to one 85 end of a fulcrum arm 25, the other end of which is pivotally attached, at 25^a to stringer 10. One end of lever 23 is connected, through an adjustable link 26, with a crank 27, and the other end of lever 23 is connected, through 90 an adjustable link 32, with a crank 33. It will be seen, therefore, that the links 26 and 32 and the lever 23 form a floating toggle by means of which the cranks 27 and 33 may be 95 swung in opposite directions when the piston 100

ton 19 is operated. A link 28 has one end pivoted to crank 27 and has the other end pivoted to a crank 29. Furthermore, a rod 30 connects a crank 31 with link 28. It will be seen, therefore, that when piston 19 moves to the right as shown in Fig. 1, the cranks 27, 29 and 31 are swung in a clockwise direction.

Referring now also to Figs. 9 and 10, the crank 29 carries a pin 29^a on which is journaled a driving link 38, the free end of which is provided with an upstanding post 39 which enters a hole 40 in the driving bar 4. It will be plain, therefore, that clockwise movement of crank 29 operates driving bar 4 to the left as shown in Fig. 1. In similar manner, crank 31 operates driving bar 3^a so that this bar moves to the left as shown in Fig. 1 when crank 31 rotates in a clockwise direction. Furthermore, crank 33 operates a crank 35 through link 34 and also operates a crank 37 through links 34 and 36. The crank 37 is connected with driving bar 4^a and crank 35 is connected with driving bar 3 in the same manner as has already been described in connection with the operation of driving bar 4 by crank 29. It will be plain, therefore, that when the piston 19 of motor M moves to the right, all of the driving bars 3, 3^a, 4 and 4^a move to the left.

30 The driving bars operate four braking bars, two of which, B and C, are located on opposite sides of rail 1 and the other two of which B^a and C^a are located on opposite sides of rail 1^a. Each of the braking bars rests directly upon the associated driving bar and in the form here shown is made up of a plurality of beam sections 6, each of which is provided at one end with a vertical tongue 16 which enters a vertical recess 15 along the confronting end of the adjacent beam section 6. With this articulated construction, a car wheel will not bind or jamb in passing from one section of the braking bar to the next section. Each of the sections 6 is provided with 45 replaceable braking shoes 7 (see Fig. 4), which shoes are arranged to engage the sides of the wheels of a car passing through the braking apparatus when the braking bars are urged toward the rail.

50 Each driving bar is provided with means for engaging the associated braking bar and moving it in directions parallel to the track rails. As best shown in Figs. 2, 4 and 8, each section of each braking bar is provided with a pair of spaced sockets 45 having a lip 48. The driving bar is provided with a plurality of driving lugs rigidly attached to the driving bar and generally rectangular in shape, one of these lugs entering each of the sockets 45 in the associated braking bar. As best shown in Fig. 8, each driving lug 41 has a projection 43 which extends over the associated lip 48 of the braking bar and limits vertical displacement of the braking bar with respect to the driving bar. It will also be seen,

from an inspection of Fig. 4, that each driving lug is provided at its lower edges with two shoulders 42 which engage the ears 14 at the sides of the channels 13 on each yoke 12. The parts are so proportioned that when the driving bars are moved to the left as shown in Fig. 1, to move the braking apparatus to its effective position, the shoulders 42 of each of the driving lugs 41, enter the recess beneath the ears 14 of the yokes 12, thereby preventing vertical displacement of the driving bars with respect to the yokes. It will also be observed from Figs. 2 and 8, that this movement of the driving bars causes the face 44 of each driving lug to engage the face 46 of the associated recess 45 in the braking bars so that braking bars are carried to the left with the driving bars.

Located adjacent each driving bar are a plurality of trunnions, each designated by the reference character D and pivotally supported by the stringers 10 and 11. Each trunnion D is connected by means of a resilient link G with the adjacent braking bar, the links G being so disposed that when the braking bar is carried to the left, it is urged toward the track rail into engagement with the flange of a wheel of a car occupying the braking apparatus. Certain of the trunnions D and links G have been omitted from Fig. 1 to simplify the drawings. A trunnion D and a resilient link G are shown in detail in Figs. 5 and 6 from which it will be apparent that the trunnion is provided at its bottom with a pivot 50 which enters a bearing wheel in a lower stringer such as stringer 8. The upper face of the trunnion D is provided with a hole 52 which receives an adjustable pivot 51 attached to the upper stringer 9. The trunnion D is therefore pivotally supported by the two stringers 8 and 9 in such manner as to withstand severe strains transmitted from the braking bar. Threaded in the trunnion D is a sleeve 53, through which passes the shank of a bolt 54. Between the head 55 of bolt 54 and the sleeve 53 is a heavy coil spring 57 which may be drawn up to a predetermined pressure by means of a nut 61 threaded on the shank of the bolt 54. The nut 61 may be locked in its adjusted position by means of a cotter pin 62. It will be seen that the pressure exerted by the spring 57 urges the nut 61 into engagement with the head of sleeve 53. Interposed between the right-hand end of the spring 57 and the left-hand end of sleeve 53 is a locking collar 58 having a rib 59 which enters a groove cut across the face of sleeve 53. Collar 58 is provided with two other ribs 60 (Fig. 6) which embrace the flattened sides of the bolt 54, thereby preventing movement of the collar with respect to the bolt. In actual practice the parts are adjusted by first drawing up the nut 61 until the spring 57 is adjusted to the desired pressure. Sleeve 53 is then

screwed into or out of the trunnion D to obtain the proper distance between the trunnion and the head of the bolt. The parts are then locked in their adjusted position by engagement of the rib 59 with the sleeve 53, thereby preventing accidental displacement of the parts. It will be seen from Figs. 5 and 6 that the head 55 of bolt 54 of the resilient link G is provided with an upstanding post 56. The post 56 of each link G enters a hole in an adjacent section 6 of the braking bar. With the parts thus far described, when the braking bars are moved to the left, as previously explained, the links G rotate toward the rail, thereby moving all of the braking bars toward the rail and into engagement with the wheels of a car passing through the braking apparatus.

Referring now to Fig. 4, it will be seen that each beam section 6 of each braking bar is provided with a flat upper portion 17 which extends away from the rail. The flat portion 17 of the braking bar protects the linkage which extends from the braking bar to the springs, and I prefer to completely close the opening between each upper stringer and the associated braking bar by means of a cover plate 63 which rests upon the flat portion 17 of the braking bar. To the lower outside edge of the cover plate are welded a plurality of guide strips 64 one adjacent each yoke 12. Each guide strip engages a shoulder on the associated yoke (Fig. 4) to prevent movement of the cover plate at right angles with the rail and the material of the weld is formed to make two shoulders 65 (see Fig. 12) which engage opposite sides of the yoke to prevent longitudinal movement of the cover plate. The cover plate 63 may, of course, be made in a number of sections for purposes of portability, and completely covers the spaces between the upper stringer and the braking bar. With this construction all parts of the apparatus are entirely protected from the elements, and from the débris which is scraped from the wheels of a car passing through the braking apparatus when the braking bars occupy their effective positions.

As shown in Figs. 4 and 8, each shoulder 43 of each driving lug 41 is provided with a lower substantially horizontal bearing surface 47. The upper face of each lip 48 of each braking bar is inclined upwardly away from the associated rail as shown at 49 in Fig. 4. Furthermore, the parts are so constructed that there is a small amount of lost motion between the bearing surface 47 of the shoulder 43 and the inclined face 49 of the lip 48. Referring particularly to Fig. 4, when the braking bar is urged into engagement with a car wheel, the tendency is for the entire braking bar to tilt in a clockwise direction, thereby lifting the shoe 7 so that this shoe engages the car wheel at a higher point,

and therefore a more effective point than would be the case if this tilting did not take place. This tilting motion of the braking bars is permitted by the lost motion between the bearing surfaces 47 and the inclined faces 49, and it will be apparent that when the braking bar rotates in a clockwise direction, the inclined surface 49 swings into parallel relation with the bearing surface 47 so that a comparatively large area is available for holding the braking bar against vertical displacement.

It will be plain from the foregoing that the driving lugs 41 on the driving bars accomplish several functions. In the first place these driving lugs transmit motion from the driving bars to the braking bars. The driving lugs also cooperate with the channels 13 in the yokes 12 and the associated ears 14 to prevent both horizontal and vertical displacement of the driving bars. Finally, the driving lugs, by cooperating with the lips 48 on the braking bars, limit the vertical displacement of the braking bars but permitting tilting of these bars to produce the most efficient braking action.

In order to facilitate the operation of the apparatus I prefer to construct the ends of the braking bars, as shown in Figs. 1 and 2. It will be plain from these figures that the ends of the braking bars are tapered away from the rail and also rounded downwardly. With this flared design, there is little or no tendency for a car to become derailed if the car enters the braking apparatus when the braking bars occupy their effective positions. Furthermore, if the car raises as it proceeds through the retarder, the wheels will simply ride on the tops of the outside braking bars until the car reaches the end of the retarder, whereupon, the wheels will be guided by the rounded and flared ends of the braking bars down onto the rails. It is assumed that cars move through the retarder in the direction shown by the arrow on Fig. 1, but both the entrance and exit ends of each braking bar are flared.

Referring now again to Fig. 1, it will be remembered that the lever 23 forming part of the toggle drive is supported at 24 in a floating pivot by an arm 25. With this arrangement it might happen that due to excessive friction in certain parts of the apparatus, operation of the piston 19 might cause unequal movement of the braking bars. For example, it might happen that when the piston 19 moves to the right, the driving bars associated with braking bars C and B^a would remain in the positions in which they then occupy, and the lever 23 would rotate about its point of connection with link 26. In this case, the braking bars C^a and B would be moved toward the rail, but the movement of these parts would be excessive, while the other braking bars would remain in position. As a

result, the parts might attain a position in which a car entering the braking apparatus would be derailed. This operation is undesirable and in order to prevent its occurrence, I have provided an equalizing unit designated in general on Fig. 1 by the reference character E. The equalizing unit is shown in detail on Fig. 7 and comprises a tube 64 having an end plate 65 which is attached to the track-way. The tube 64 is also provided with an end plate 66. Located within the tube 64 is a coil spring 74. Interposed between the left-hand end of spring 74 and the end plate 66 is a member 72 having a centrally located hole 75. A similar member 73, provided with a centrally located hole 69, is interposed between the other end of spring 74 and the end plate 65. A rod 67 passes through the holes 69 and 75 in members 73 and 72, and also passes through a hole 70 in end plate 66. The upset end 68 of rod 67 engages the outer surface of the member 73. Threaded on rod 67 is a sleeve 71 which enters the hole 70 in the end plate 66 and bears against the outer surface of member 72. The end plate 66 is screwed into or out of the tube 64 until the spring 74 is under the desired pressure, and the parts are then secured by bolt 66^a. Sleeve 71 is then screwed on rod 67 until it engages the member 72 when the upset end 68 of the rod is tight against the member 73. Sleeve 71 is then locked in its adjusted position by means of nut 76. The free end of rod 67 is attached to the arm 25 (Fig. 1) adjacent its free end and it will therefore be plain that the equalizing device E tends to hold the arm 25 in its central position so that when the motor M is operated, the braking bars are moved by equal amounts. For example, if the arm 25 tends to move toward the left, as seen in Fig. 1, the rod 67 (Fig. 7) moves toward the left and carries with it the member 73, thereby tending to compress spring 74. In similar manner, if the arm 25 tends to move to the right, the rod 67 also moves to the right, and causes the sleeve 71 to urge the member 72 to the right and compresses spring 74. The equalizing unit E therefore opposes any movement of the arm 25 by an amount which depends upon the strength of the spring 74. The parts are so adjusted that the force exerted by spring 74 is just sufficient to overcome the normal forces of friction in the braking apparatus. When a car is in the braking apparatus and the braking bars are being urged against the car wheels by the force of the motor M, the equalizing unit E is operated in one direction or the other to permit the braking apparatus to compensate for variations in the gauge of the car wheels or for any inequalities in the trucks.

Referring now to Fig. 11, I have shown one form of apparatus for controlling the braking apparatus described hereinbefore.

65 The cylinder 18 of motor M contains, in ad-

dition to the piston 19, an auxiliary piston 20, which at times occupies the projected position in which it is shown in the drawings, to limit the stroke of the main piston 19. At other times piston 20 is moved to the extreme right-hand end of the cylinder to permit a larger stroke for piston 19. The sealing ring of piston 20 is located at 20^a in the drawings and the parts are so proportioned that even when the piston occupies its projected position in which it is illustrated in the drawings, the piston does not close the pipe 81 which communicates with the side of the cylinder. Piston 20 is provided with flutes by means of which the pipe 81 may at all times communicate with the region between pistons 20 and 19.

The motor M is controlled in part by five magnet valves designated by the reference characters K¹, to K⁵, respectively. Valve K¹ is arranged when energized to connect pipe 81 with atmosphere, but when the valve is de-energized, this pipe is blanked. When valve K² is de-energized, stem 79 occupies a position in which pipe 81 is disconnected from pipe 80, but when valve K² is energized, stem 79 moves downwardly and fluid pressure, usually air, is then supplied to pipe 81, from a suitable source not shown in the drawings, through pipe 80. When valve K³ is de-energized, the right-hand end of cylinder 18, behind piston 20, is connected through pipe 82 with pipe 80 and is therefore supplied with fluid pressure. When valve K³ is energized, however, valve stem 79 moves downwardly, thereby disconnecting pipe 82 from pipe 80 and connecting pipe 82 with atmosphere so that the right-hand end of cylinder 18 is then connected with atmosphere. Pipe 83 communicates with the left-hand end of cylinder 18, and when valve K⁴ is de-energized, this pipe is sealed, but when valve K⁴ is energized, pipe 83 is connected with atmosphere. When valve K⁵ is energized, pipe 83 is connected with pipe 80 to supply fluid pressure to the left-hand end of cylinder 18.

The valves K¹ to K⁵, inclusive, are controlled in part by three circuit controllers S¹, S² and S³ which are operated by piston 19. When the piston occupies its left-hand position, as shown in the drawings, so that the braking apparatus occupies its open or ineffective position, contact 87—88 of circuit controller S² and contact 90—91 of circuit controller S³ are closed. When the piston moves to the right, contact 85—86 of circuit controller S¹ closes, and when the piston reaches a position for which the braking bars just engage the wheels of a car in a braking apparatus, contact 87—88 of circuit controller S² and contact 90—91 of circuit controller S³ open, and contact 87—89 of circuit controller S² and contact 91—92 of circuit controller S³ close.

The reference character P¹ designates a

circuit controller comprising a Bourdon tube 94 connected with pipe 81 and subjected to the pressure in the region between pistons 20 and 19 in the cylinder 18. The Bourdon tube 94 controls a contact 93—93^a which is closed at all times except when the pressure exceeds a predetermined amount, such for example, as 30 pounds per square inch, which is just sufficient to hold the braking apparatus in its ineffective or open position. Circuit controllers P² and P³ are similar to circuit controller P¹ except that the Bourdon tubes 94 of these circuit controllers are connected through pipes 84 and 83 with the left-hand end of cylinder 18. The circuit controllers P² and P³ are arranged to operate in succession as the pressure in the left-hand end of cylinder 18 increases. For example, for all pressures below 10 pounds per square inch, contacts 93—93^a of both circuit controllers are closed. When the pressure exceeds 10 pounds per square inch, contact 93—93^a of circuit controller P² opens. If the pressure exceeds 20 pounds per square inch, contact 93—93^b of circuit controller P² closes. In similar manner, the circuit controller P³ is adjusted to open contact 93—93^a at 55 pounds per square inch and to close contact 93—93^b at 65 pounds per square inch.

The reference character J designates a manually operable switch having a lever 95 movable into engagement with a selected one or ones of a plurality of fixed contacts designated 96 to 102, inclusive. As shown in the drawings, the switch J occupies its "off" position, so that contacts 95—96 and 95—97 are closed but all of the valves K are de-energized. Since valve K³ is de-energized, the full line pressure existing in pipe 80 is admitted to the right-hand end of cylinder 18 so that piston 20 occupies its projected position. Furthermore, valves K¹ and K² are both closed, but the region between pistons 19 and 20 is charged to a pressure of 30 pounds per square inch. If the pressure in this region falls below this value, the circuit controller P¹ closes contact 93—93^a and current then flows from battery 103, over contact 95—96 of switch J, wire 122, contact 93—93^a of circuit controller P¹, wire 123, winding of magnet valve K², and common wire 107 back to battery 103. When this happens, the valve K² opens and admits fluid pressure to pipe 81, and therefore to the region between pistons 19 and 20, until the pressure in this region reaches 30 pounds per square inch, whereupon, contact 93—93^a opens, and valve K² becomes de-energized. With the switch J in its "off" position, then, the braking apparatus is held in its ineffective or open position.

I will now assume that the operator wishes to move the braking apparatus to its closed or effective position. If he wishes to make a comparatively light brake application, he

closes contact 95—98. This does not affect valve K³ but a circuit is now closed from battery 103, over contact 95—98 of switch J, wire 104, contact 87—88 of circuit controller S², wires 105 and 106, winding of valve K⁵, and common wire 107 back to battery 103. This circuit is provided with a branch which passes from wire 106, through wires 108 and 109, winding of valve K¹ and common wire 107 back to battery 103. Valves K¹ and K⁵ therefore become energized. The energization of valve K¹ connects pipe 81 with atmosphere, thereby exhausting the pressure to the right of piston 19. Furthermore, the energization of valve K⁵ admits fluid pressure to the left-hand end of cylinder 18 thereby urging the piston toward the right. This movement of the piston is transmitted, through the apparatus shown in Fig. 1, to the braking bars, thereby moving the braking bars toward the rails. It should be noted that the pressure available to commence the movement of the braking bars may be built up to full line pressure so that the response of the apparatus is very rapid. When the braking bars have attained a position corresponding to the working range of the apparatus, that is, when the bars are in position to engage the wheels of a car in the braking apparatus, contact 87—88 of circuit controller S² opens to interrupt the circuit just traced for valves K¹ and K⁵, and contact 87—89 closes. If the pressure in the left-hand end of cylinder 18 is now below 10 pounds per square inch, a branch will be completed for the circuit previously traced for valve K⁵ which may be traced from wire 104, through contact 87—89 of circuit controller S², wire 110, contact 93—93^a of circuit controller P², wires 114, 115 and 106, winding of valve K⁵, and common wire 107, back to battery 103. The valve K⁵ therefore remains energized until the pressure has exceeded 10 pounds per square inch, whereupon, the contact 93—93^a of circuit controller P² opens, to de-energize magnet valve K⁵. It is probable, however, that during the preliminary movement of the piston, the pressure in the left-hand end of the cylinder exceeded 20 pounds per square inch, so that contact 93—93^b of circuit controller P² is closed. Under these conditions, when the braking bars reach a position at which contact 87—89 of circuit controller S² closes, a circuit is completed from battery 103, through contact 95—98 of switch J, wire 104, contact 87—89 of circuit controller S², wire 110, contact 93—93^b of circuit controller P², wires 111, 112 and 113, winding of valve K⁴, and wire 107 back to battery 103. Valve K⁴ is then energized, thereby opening pipe 83 to atmosphere and exhausting the left-hand end of cylinder 18 until the pressure has been reduced below 20 pounds per square inch. It will be plain from the foregoing that when switch J has contact 95—98 closed, the piston

19 will be urged to the right by pressure between 10 and 20 pounds per square inch. The movement of piston 19 to the right is limited by the auxiliary piston 20, and the parts are so proportioned that the movement of the lever 23 (Fig. 1) caused by this movement of piston 19 does not bring the toggle to its dead-center position. If, therefore, a car enters the braking apparatus, the braking bars may be forced away from the rail, thereby transmitting the re-action of the wheels, through the driving bars and the mechanical linkage including the toggle, to the piston 19. As a result, the piston may be moved slightly to the left, thereby cushioning the braking action of the apparatus against the volume of air in cylinder 18.

If the operator desires to cause a more powerful brake application, he closes contact 95-99 of control switch J. The operation of the apparatus is then the same as that just described in connection with contact 95-98 of the control switch with the single exception that the circuit controllers P³ and S³ are now substituted for the circuit controllers P² and S² in the control of valves K⁴ and K⁵. Under these conditions, then, the piston 19 is forced to the right and is held against piston 20 by fluid pressure between 55 to 65 pounds per square inch.

If the operator closes contact 95-100 of switch J a circuit is completed for valve K⁵ from battery 103, through contact 95-100 of switch J, wires 120 and 108, winding of valve K⁵, and common wire 107 back to battery 103. With the control switch J in this position, therefore, valve K⁵ is held energized, and since valve K⁴ is now closed, the full line pressure is supplied to the left-hand end of cylinder 18 and holds piston 19 against piston 20.

If it is desirable to apply still higher braking forces the operator moves the switch J to a position in which lever 95 engages contacts 100 and 102. Under these conditions, the circuit previously traced for valve K⁵ is closed so that this valve is energized to supply full line pressure to the left-hand end of cylinder 18. In addition, a circuit is now completed from battery 103, over contact 95-102 of switch J, wire 121, winding of valve K³, and common wire 107 back to battery 103. Valve K³ is therefore energized so that the stem 79 reverses and the right-hand end of cylinder 18 is exhausted to atmosphere. The full line pressure now supplied to the left-hand end of the cylinder moves piston 19 and piston 20 to the extreme right-hand end of the cylinder. The construction of the parts is such that this additional movement of the piston 19 brings lever 23 (Fig. 1) into a position in which the toggle of which it forms a part is on dead-center. When the parts occupy these positions, the reaction of the wheels cannot be transmitted back to the

piston 19, and the entire force exerted by the springs of the resilient links G is available to force the braking bars against the wheels of a car.

When the braking bars are being urged against the wheels of a car, the inner braking bars B and C^a are operated together from lever 23 through link 32, and the outer braking bars B^a and C are operated together from lever 23 through link 32. But it will be remembered that the lever 23 is supported on a floating pivot by the arm 25. It follows that with this construction, the reaction of the inner braking bars is balanced against the outer braking bars, the arm 25 moving to a position in which the reactions are equal. Of course, the unit E biases the arm 25 to a central position, but the force exerted by this unit is insignificant compared with the large forces applied to the braking bars by the motor M. It will be manifest, therefore, that with braking apparatus constructed in accordance with my invention, the reactions of the inner and outer braking bars are substantially equalized.

It should be observed that if the operator moves switch J from a position corresponding to a high braking force, to a position corresponding to a lower braking force, the apparatus immediately and automatically reduces the braking pressure to the value corresponding to the new position of the switch, in a manner which will be apparent from the drawings without tracing the sequence of operation in detail.

In order to restore the apparatus to its open or ineffective position, the operator moves switch J to the position in which it is illustrated in the drawings. Under these conditions, valve K³ is de-energized, so that line pressure is admitted to the right-hand end of cylinder 18 and the auxiliary piston 20 is projected into the position in which it is shown in the drawings. The closing of contact 95-96 completes the circuit for valve K² over contact 93-93^a of circuit controller P¹ which was previously described, and this valve therefore opens to admit fluid pressure to pipe 81, and hence to the region between pistons 19 and 20. Furthermore, the closing of contact 95-97 of switch J permits current to flow from battery 103, through contact 95-97 of switch J, wire 124, contact 85-86 of circuit controllers S¹, wires 125 and 113, winding of valve K⁴, and common wire 107 back to battery 103. Valve K⁴ is therefore energized to exhaust the left-hand end of cylinder 18 to atmosphere. Furthermore, since valve K² is open, the pressure on the right-hand side of piston 19 moves this piston to the left to restore the braking apparatus to the open position in which it is illustrated in Fig. 1. When the pressure in the region between pistons 19 and 20 exceeds 30 pounds per square inch,

circuit controller P¹ operates to de-energize valve K² and prevent wasting of air pressure. When piston 19 reaches its left-hand position, contact 85—86 of circuit controller S¹ opens, thereby de-energizing valve K⁴ and sealing pipe 83 to prevent the escape of fluid from the cylinder.

It should be noted that when the parts are in the position in which they are illustrated in the drawings, if the valve K² leaks, the pressure between pistons 19 and 20 may be built up to full line pressure, but this is not dangerous or undesirable, because, when the switch J is operated to actuate the braking apparatus, valve K¹ is opened to exhaust the pressure to the right of piston 19.

Furthermore, should valve K⁵ leak, pressure might build up on the left-hand side of piston 19 to start the movement of this piston to the right and operate the braking apparatus toward its closed position. As soon as the movement of the piston commences under these conditions, contact 85—86 of circuit controller S¹ closes, thereby completing the circuit for valve K⁴ and exhausting the left-hand end of cylinder 18 to atmosphere. Pressure on the right-hand side of piston 19 will then restore the piston to its left-hand position, whereupon, contact 85—86 will open to de-energize valve K⁴.

With braking apparatus embodying my invention, the apparatus may be readily adjusted to compensate for brake shoe wear. Thus, by varying the length of the adjustable link 26, the wear may be taken up in the shoes on the braking bars which bear against the outsides of the wheels of cars passing through the apparatus. In similar manner, the inside braking bars may be adjusted to compensate for wear by varying the length of the adjustable link 32. It will be observed that the arms of cranks 29 and 31 make obtuse angles, and that the arms of cranks 35 and 37 make acute angles. Furthermore, the links 28 and 34 are disposed at angles with the rods 30 and 36. With this arrangement, the apparatus has a substantially constant mechanical advantage, regardless of adjustments in the lengths of the links 26 and 32 to compensate for wear as described above. It is therefore possible to compensate for maximum wear in the brake shoes without changing the adjustment of the resilient links G.

One advantage possessed by braking apparatus embodying my invention is that the entire weight of the apparatus is supported on the cradles formed by the stringers and cross yokes, even the driving cranks and operating linkage being supported in columns made up of rolled channels which are bolted directly to the stringers as shown in Figs. 1 and 2. It follows that all of the high internal stresses, which are developed as a result of applying pressure to the car wheels

are absorbed within the cradles and associated parts, only the actual retarding forces being transmitted to the cross ties.

It should also be pointed out that all parts of the braking apparatus are electrically isolated from the track rails, even the yokes being spaced from the rails which are of course supported on the ties by the usual chairs. With this arrangement it will be apparent that the usual track circuits employed in railway signaling may be run directly through the braking apparatus without interfering with the operation of such circuits.

Although I have herein shown and described only one form of railway braking apparatus embodying my invention, it is understood that various changes and modifications may be made therein within the scope of the appended claims without departing from the spirit and scope of my invention.

Having thus described my invention, what I claim is:

1. Railway braking apparatus comprising a braking bar located in the trackway, a cylinder, a first piston reciprocable in said cylinder and operatively connected with said braking bar, a second piston in said cylinder, and means for selectively operating said second piston to regulate the stroke of said first piston.

2. Railway braking apparatus comprising a braking bar located in the trackway, a cylinder, a piston reciprocable in said cylinder and operatively connected with said braking bar, means for selectively supplying fluid pressure to said cylinder on either side of said piston to operate said braking bar, and manually controlled means in said cylinder for at times limiting the movement of said piston in one direction.

3. Railway braking apparatus comprising a braking bar located in the trackway, a cylinder, a first piston in said cylinder, manually controlled means for moving said first piston to either of two positions, a second piston in said cylinder, means for at times admitting fluid pressure to said cylinder to move the second piston into engagement with said first piston, and linkage connecting said second piston with said braking bar in such manner that movement of the second piston toward the first piston drives the braking bar toward its closed position.

4. Railway braking apparatus comprising a braking bar located in the trackway, a cylinder, a first piston in said cylinder operatively connected with said braking bar, means for moving said piston in one direction to urge said bar toward its braking position, a second piston in said cylinder, and means for driving said second piston in the opposite direction to limit the stroke of said first piston.

5. In combination, a railway braking bar

located in the trackway, a cylinder, a first piston movable in said cylinder between one end of the cylinder and an intermediate point, a second piston movable in said cylinder between the other end of the cylinder and said first piston, means for selectively supplying fluid pressure to said cylinder between each piston and the adjacent end of the cylinder, and linkage connecting said second piston with said braking bar.

6. In combination, a railway braking bar located in the trackway, a cylinder, a first piston movable in said cylinder between one end of the cylinder and an intermediate point, a second piston movable in said cylinder between the other end of the cylinder and said first piston, means for selectively supplying fluid pressure to said cylinder between each piston and the adjacent end of the cylinder and to the cylinder between said pistons, and linkage connecting said second piston with said braking bar.

7. In combination, a railway braking bar located in the trackway, a cylinder, a first piston movable in said cylinder between one end of the cylinder and an intermediate point, a second piston movable in said cylinder between the other end of the cylinder and said first piston, manually controlled means for selectively connecting said cylinder between the first piston and said one end of the cylinder with atmosphere or a source of fluid pressure, manually controlled means for connecting said cylinder between said pistons with atmosphere or with a source of fluid pressure, manually controlled means for connecting said cylinder between said second piston and the other end of the cylinder with atmosphere or with a source of fluid pressure, and linkage 40 connecting said second piston with said braking bar.

8. In combination, a railway braking bar located in the trackway, a cylinder, a first piston movable in said cylinder between one end of the cylinder and an intermediate point, a second piston movable in said cylinder between the other end of the cylinder and said first piston, manually controlled means for selectively connecting said cylinder between the first piston and said one end of the cylinder with atmosphere or a source of fluid pressure, a circuit controller responsive to the pressure in the cylinder between said pistons, means for at times connecting said cylinder between said pistons with atmosphere, means controlled by said circuit controller for at other times connecting said cylinder between said pistons with a source of fluid pressure, a manually operable circuit controller, a plurality of contacts responsive to the pressure in said cylinder between said second piston and the other end of the cylinder, means controlled by said manually operable circuit controller for at times connecting the cylinder between the second piston

and the other end of the cylinder with atmosphere, means controlled by said second piston for at other times supplying fluid pressure to the cylinder between said second piston and said other end of the cylinder under the control of a selected one of said contacts depending upon the position of said manually operable circuit controller and linkage connecting said second piston with said braking bar.

9. Railway braking apparatus comprising two braking bars located on opposite sides of a track rail, a toggle comprising a lever and two arms connected respectively with said two braking bars, means for at times moving said lever in one direction to drive said bars toward said rail, and means for at times causing further movement of said lever to place the toggle on dead-center, and means for moving said lever in the opposite direction.

10. Railway braking apparatus comprising two braking bars located on opposite sides of a track rail, a toggle comprising a lever and two arms connected respectively with said two braking bars, a motor for driving said lever, and manually controlled means for controlling the stroke of said motor.

11. Railway braking apparatus comprising two braking bars located on opposite sides of a track rail, an arm having one end pivoted in the trackway, a toggle comprising a lever pivoted on the free end of said arm and operating said braking bars, and a motor for driving said lever.

12. Railway braking apparatus comprising two braking bars located on opposite sides of a track rail, an arm having one end pivoted in the trackway, a lever pivoted on the free end of said arm and operatively connected with said braking bars, a motor for driving said lever, and an equalizing device biasing said arm to a normal position but permitting movement of the arm away from such position in response to the reaction of a car wheel engaged by said braking bars.

13. In a car retarder, an arm pivoted at one end in the trackway, a tube having fixed end plates and pivotally supported in the trackway, a compressed spring in said tube, a first member interposed between one end of said spring and one end plate of said tube, a second member interposed between the other end of said spring and the other end plate of said tube; a rod having an upset end outside said first member and said rod passing through said first member, said second member, and said other end plate, means for fastening the free end of said rod to the free end of said arm; a sleeve fastened to said rod and engaging the outer side of said second member, a lever pivoted on the free end of said arm, two braking bars on opposite sides of a track rail and operatively con-

nected with said lever, and a motor for operating said lever.

14. Railway braking apparatus comprising a pair of flat vertically spaced stringers located in the trackway parallel with a track rail, a plurality of trunnions pivoted between said stringers, a braking bar between said stringers and said rail, a plurality of resilient links separately connecting said braking bar with said trunnions, and a driving bar operatively connected with said braking bar and movable parallel with said rail to urge the braking bar toward the rail.

15. Railway braking apparatus comprising a pair of flat vertically spaced stringers located in the trackway parallel with a track rail, a plurality of trunnions pivoted between said stringers, a braking bar between said stringers and said rail, a plurality of resilient links separately connecting said braking bar with said trunnions, a driving bar operatively connected with said braking bar and movable parallel with said rail to urge the braking bar toward the rail, and a flat cover plate overlapping said braking bar and closing the space between the top stringer and the bar.

16. Railway braking apparatus comprising two pairs of stringers located parallel with a track rail and one pair disposed on each side of the rail, a plurality of yokes extending transversely beneath the track rail and each having its two ends fastened to the pairs of stringers, respectively, two series of trunnions pivoted respectively between said pairs of stringers, two braking bars one located between each pair of stringers and the track rail, means for moving said braking bars in a direction parallel with the track rail, and a plurality of resilient links separately connecting said trunnions with the associated braking bar so that the bars are urged toward the rail when the bar is moved parallel with the rail in one direction.

17. Railway braking apparatus comprising a pair of vertical spaced stringers located parallel with a track rail, a braking bar located between said stringers and said rail, resilient linkage connecting said bar and said stringers, a plurality of yokes fastened to said stringers, and a flat cover plate overlapping said braking bar to protect said linkage and provided with a plurality of guide strips for separately engaging said yokes.

18. Railway braking apparatus comprising two stringers extending parallel with a track rail one on each side of the rail and resting on the usual cross-ties, a plurality of yokes each having its ends attached to said stringers respectively and each extending transversely beneath said rail, two braking bars one located between each stringer and said rail, means for moving said braking bars parallel with said rail, and a plurality of resilient links pivotally connect-

ing each braking bar with the adjacent stringer in such manner that the braking bars are urged toward said rail when such bars are moved parallel with said rail in one direction.

19. Railway braking apparatus comprising two stringers extending parallel with a track rail one on each side of the rail and resting on the usual cross-ties, a plurality of yokes each having its ends attached to said stringer respectively and each extending transversely beneath said rail, two driving bars supported by said yokes, a motor for operating said driving bars, two braking bars one located between each stringer and said rail and operatively connected with said driving bars, respectively, and resilient links pivotally connecting each braking bar with the associated stringer in such manner that movement of the driving bars parallel with a track rail causes movement of said braking bars at right angles with said rails.

20. Railway braking apparatus comprising two stringers extending parallel with a track rail one on each side of the rail and resting on the usual cross-ties, a plurality of yokes each having its ends attached to said stringer respectively and each extending transversely beneath said rail, two driving bars supported by said yokes, a motor for operating said driving bars, two braking bars one resting upon and operatively connected with each said driving bar, and resilient links connecting each braking bar with the associated stringer in such manner that the braking bars are urged toward the track rail when said motor drives said driving bars in one direction.

21. Railway braking apparatus comprising two stringers extending parallel with a track rail one on each side of the rail and resting on the usual cross-ties, a plurality of yokes each having its ends attached to said stringers respectively and each extending transversely beneath said rail and each provided with a channel, a driving bar reciprocable in said channels, a motor operating said driving bar, and a braking bar operatively connected with said driving bar.

22. Railway braking apparatus comprising a driving bar located in the trackway and provided with a hole, a crank pivoted in the trackway, a motor operatively connected with said crank, a driving link having one end pivotally connected with said crank and provided with a post entering said hole, means for preventing movement of said driving bar vertically or at right angles with a track rail while permitting movement of the driving bar parallel with said rail, a braking bar having a socket, a lug on said driving bar entering said socket, a trunnion pivoted in the trackway, and a resilient link containing said braking bar and said trunnion.

23. Railway braking apparatus compris-

- ing two stringers extending parallel with a track rail one on each side of the rail and resting on the usual cross-ties, a plurality of yokes each having its ends attached to said stringers respectively and each extending transversely beneath said rail, and each provided with a channel having inwardly turned ears, a driving bar reciprocable in said channels, means for moving said driving bars parallel with said rail, a braking bar having a socket, a lug on said driving bar entering said socket and at times engaging said ears to prevent vertical displacement of said driving bar, a lip on said braking bar engaging a bearing surface on said lug to limit vertical movement of said braking bar, and means for urging said braking bar toward the rail when the braking bar is moved parallel with the rail in one direction.
- 20 24. Railway braking apparatus comprising a driving bar located in the trackway parallel with a track rail, a motor operatively connected with said driving bar, a braking bar having a socket, a lug on said driving bar entering said socket and having a substantially horizontal bearing surface spaced above said bar, a lip on said braking bar sloping upwardly away from said rail and engaging said bearing surface, and means for urging said braking bar toward said rail when the braking bar is moved parallel with the rail in one direction.
- 25 25. Railway braking apparatus comprising a driving bar reciprocable in the trackway, means for moving said driving bar parallel with a track rail, a trunnion pivoted in the trackway, a braking bar, a resilient link connecting said braking bar with said trunnion, and means for operatively connecting said driving bar with said braking bar to permit slight tilting of the wheel engaging surface of the braking bar when the braking bar is urged against a wheel on said rail as the driving bar moves in one direction.
